FRAME FOR A COUCH

Howard Philip Doner, R.R. 2, Whitby,
Ontario, Canada

Filed Feb. 24, 1967, Ser. No. 5,945

Claims priority, application Canada Oct. 31, 1966

Term of patent 14 years

(Cl. D15—11)

I claim:

The ornamental design for a frame for a couch, as shown.
